DRIVE-SPRING FASTENER

Ferdinand Fengler, Bristol, Conn., assignor to The
E. Ingraham Company, Bristol, Conn., a corpora-
tion of Connecticut

Application April 23, 1946, Serial No. 664,377

4 Claims. (Cl. 58—52)

1

The present invention relates in general to timepieces and more especially to improved means for securing an element such as a spring to the frame of the timepiece.

Heretofore, the free or outer ends of elements such as the mainsprings and alarm springs of timepieces have been made fast to the frame by fastening-means comprising, almost universally, a separate clamp or a clamp formed integrally on the outer end of the spring and secured to one of the pillars of the frame by a rivet or similar fastening-means. This construction is not only relatively expensive but has necessitated that the entire frame be disassembled to replace a broken spring.

An object of the invention is to provide improved means for securing the outer or free end of a spring to the frame of a timepiece.

A further object is to provide spring-fastening means to enable a spring to be disengaged from the frame of a timepiece without disassembling the frame.

A still further object is to provide an apertured tang on the outer end of a mainspring, the tang being adapted to fit over an extremity of one of the pillars of the frame to removably secure the outer end of the spring thereto.

With the above and other objects in view, as will appear to those skilled in the art from the present disclosure, this invention includes all features in the said disclosure which are novel over the prior art and which are not claimed in any separate application.

In the accompanying drawings, in which certain modes of carrying out the present invention are shown for illustrative purposes:

Fig. 1 is a fragmentary plan view of the frame of a timepiece embodying the improved spring-fastening means of this invention;

Fig. 2 is a front elevation of the frame and spring-fastening means shown in Fig. 1;

Fig. 3 is an enlarged fragmentary plan view of the outer end of the mainspring in the horizontal plane of line 3—3 of Fig. 1; and

Fig. 4 is a fragmentary sectional elevation in the direction of arrows 4—4 of Fig. 1.

Referring to the drawings which illustrate an exemplary embodiment of the invention, the timepiece-frame is indicated generally at 10 and comprises front and rear movement-plates 11 and 12 held in spaced parallel relationship by pillars 13. Mounted between the front and rear movement-plates is a time-train indicated generally at 14, and an alarm-train indicated generally at 15. The time-train 14 comprises a gear-train of

2

conventional construction driven by the force of a wound spiral-mainspring such as shown at 16, the latter being supported on a winding-arbor 17 which is rotatably mounted at its opposite ends in the front and rear movement-plates. The rear extremity of the winding-arbor 17 is provided with the usual winding-key 18 for manually rotating the arbor 17. The mainspring 16 is secured at its inner end 19 to the winding-arbor 17, the connection between the inner end of the spring and the arbor being the usual type of fastening-means 20, as shown in Fig. 1.

The opposite or outer free end 21 of the mainspring 16 is adapted to be fastened to the frame 10 in a manner such as to enable the outer end 21 of the spring to be readily attached thereto, and removed therefrom with dispatch and without necessitating the disassembly of the entire frame. To this end, the outer extremity 21 of the mainspring 16 is reduced in width, as shown in Fig. 2, the reduced portion constituting a tongue 22 having a radius at its outer end and a longitudinal slot 23. The slot 23 is substantially rectangular, its longitudinal axis being coincident with the longitudinal axis of the tongue 22.

Mounted in the slot 23 is a substantially T-shaped tang indicated generally at 24; comprising a relatively-thin sheet-metal member 30 having a substantially-rectangular base 25 exceeding in length the length of the slot 23, but substantially equal in thickness to the width thereof (see Fig. 2); and a reach 26, the width of the latter being substantially less than the width of the slot 23 (see Fig. 3) and offset from and in a plane substantially parallel to the plane through the longitudinal edges of the base 25, as shown in Fig. 4. An aperture 27 is provided in the outer extremity of the reach 26. The inner end of the reach 26 is joined integrally to the base 25 by the stepped substantially-square shoulders 28, the distance between the respective shoulders being substantially equal to the width of the slot 23 in the outer end of the spring.

45 The tang is adapted to be inserted into the slot 23 reach-end first and to be thrust forwardly therein until the shoulders 28 engage in the corresponding edges of the slot 23. It will be noted that the original height of each shoulder 50 as indicated by broken lines in Fig. 3, exceeds the thickness of the tongue-portion 22 of the spring 21. In accordance with this construction, the tang may be secured in the slot 23 of the tongue 22 by swaging or peening over the upper edges 55 of the shoulders 28, to form beads or flanges 29

overlying the adjacent face of the tongue 22 which, in conjunction with the extremities 30 of the base 25, overlying the opposite face of the tongue 22 serve to firmly secure the tang in the slot 23 in the outer end of the spring.

As shown in the drawings, the outer end of the spring 21 is adapted to be fastened to the frame 10 by engaging the apertured tang 26 over the upwardly-extending threaded extremity 31 of one of the pillars 13 of the frame, and to be secured thereon by the pillar-collar 32 and nut 33. When so secured to the frame, the offset-portion 26 of the tang engages the outer face of the rear movement-plate 12 (see Fig. 4), whereby attachment of the tang to the frame or disconnection therefrom is readily accomplished by simply removing the single nut 33 and collar 32 from the threaded extremity of the pillar 31, thus obviating the necessity for disassembling the entire frame.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended to be embraced therein.

I claim:

1. In a timepiece having a frame comprising front and rear movement-plates, pillars to support said plates in spaced parallel relationship, a gear-train, a spring for driving said gear-train said spring having an aperture in its outer end, a spring-winding arbor and means to secure the inner end of said spring to said arbor; of means to removably secure the outer end of said spring to said frame comprising an apertured tang secured permanently in the aperture in the outer end of said spring in a plane substantially at right angles to the plane of the outer end of said spring and constructed and arranged to cooperatively engage a pillar of said frame.

2. In a time piece having a frame comprising front and rear movement-plates, pillars to support said plates in spaced parallel relationship, a gear-train, a spring for driving said gear train said spring having an aperture in its outer end, a spring-winding arbor and means to secure the inner end of said spring to said arbor; of means to removably secure the outer end of said spring to said frame comprising a tang having a base-portion secured permanently in the aperture in the outer end of said spring, and an apertured reach, said apertured reach lying in a plane sub-

stantially at right angles to the plane of the outer end of said spring and constructed and arranged to cooperatively engage an extremity of a pillar of said frame.

3. In a timepiece having a frame comprising front and rear movement-plates, pillars to support said plates in spaced parallel relationship, a gear-train, a spring for driving said gear-train said spring having an aperture in its outer end, a spring-winding arbor and means to secure the inner end of said spring to said arbor; of means to removably secure the outer end of said spring to said frame comprising a tang having a base-portion secured permanently in the aperture in the outer end of said spring, and an apertured reach, said reach being offset from said base and lying in a plane substantially at right angles to the plane of the outer end of said spring so as to make face-to-face contact with the rear face of the rear movement-plate the aperture of said reach being adapted to fit over an extremity of a pillar of said frame.

4. In a timepiece having a frame comprising front and rear movement-plates, pillars to support said plates in spaced parallel relationship, a time-train, a mainspring for driving said time-train said mainspring having an aperture in its outer end, a mainspring-winding arbor and means to secure the inner end of said mainspring to said arbor; of means to removably secure the outer end of said spring to said frame comprising a tang having a base-portion swaged in the aperture in the outer end of said mainspring and an apertured reach, said apertured reach lying in a plane substantially at right angles to the plane of the outer end of said spring and constructed and arranged to fit over an extremity of a pillar of said frame, and a member to removably secure said tang to the extremity of said pillar.
